US00D608393S

(12) **United States Design Patent**
Koreska

(10) **Patent No.:** **US D608,393 S**
(45) **Date of Patent:** **** Jan. 19, 2010**

(54) **WRITING UTENSIL**

(75) Inventor: **Peter Koreska**, Vienna (AT)

(73) Assignee: **Kores Holding Zug AG**, Zug (CH)

(**) Term: **14 Years**

(21) Appl. No.: **29/331,990**

(22) Filed: **Feb. 6, 2009**

(30) **Foreign Application Priority Data**

Aug. 7, 2008 (AT) ..... MU 662/2008

(51) **LOC (9) Cl.** **19-06**

(52) **U.S. Cl.** **D19/50**

(58) **Field of Classification Search** ..... D19/35, D19/36, 41-51, 53-57; 24/11 F, 11 P, 11 R; 401/52, 99, 100, 104-109, 192, 195, 196

See application file for complete search history.
